MOP

Karl I. Strand, Huntington Park, Calif.

Application October 30, 1941, Serial No. 417,108

2 Claims. (Cl. 15—147)

My invention relates to a mop, and more particularly to a dust mop that will avoid marring furniture during the use thereof.

An object of the invention is to provide a dust mop whose mop portion is of relatively small vertical height when in operative position, in order that the mop portion may be pushed under furniture, the body of which is close to the floor.

Another object of the invention is to provide a non-metallic mopping element that may be removed from the rest of the mop, for shaking, washing, repair or replacement.

Still another object is to provide an elastic body portion for supporting the mopping element.

The invention also comprises novel details of construction and novel combinations and arrangements of parts, which will more fully appear in the course of the following description. However, the drawing merely shows and the following description merely describes one embodiment of the present invention, which is given by way of illustration or example only.

In the drawing, like reference characters designate similar parts in the several views.

Fig. 1 is a face view of a mop embodying the foregoing objects, with the handle partly broken away.

Fig. 2 is an enlarged, transverse section taken on the bent line 2—2 of Fig. 1.

Fig. 3 is an enlarged transverse section taken on the line 3—3 of Fig. 1.

Referring more in detail to the drawing, the reference numeral 4 generally designates the handle, which is provided with a tapered end 5 having a shoulder 6 against which abuts a ferrule member 7 of a spring metal clamp 8.

The clamp 8 also has angularly arranged, relatively smaller ferrule members 9 and 10. Normally upper webs 12 and 13 connect the normally upper portion of the ferrule 7 with similar portions of the smaller ferrules 9 and 10, respectively. Normally lower webs 14 and 15 connect the normally lower portion of the ferrule 7 with similar portions of the smaller ferrules 9 and 10, respectively. The ferrules 7, 9 and 10, and the webs 12 to 15 are integral with each other and together form the spring clamp 8 which is separable at 16 for assembling purposes.

The ferrule 7 is tapered to fit the tapered end 5 of the handle. A screw 17 fastens said tapered end 5 in the ferrule 7. To clamp together the normally upper and lower portions of the clamp 8, a bolt 18 and an engaging wing nut 19 are provided.

Clamped between the opposed members of the

ferrules 9 and 10 are ends 21 and 22 of a bowed, elastic body member 20. Such ends are countersunk circumferentially, as suggested at 23 and 24, to provide gripping grooves for the ferrules 9 and 10. The body member 20 may be solid, as shown in the drawing, or, it is believed clear without further illustration, that the body member 20 may be tubular.

It will be noted that the ends 21 and 22 of the elastic body member 20 not only toe in, to provide a compact arrangement in mounting same on the handle, but the ends 21 and 22 of such member project beyond the edges of the metal clamp 8, to protect furniture from such edges.

Slid lengthwise of the body member 20 (when an end is released from the spring clamp 8) is a fabric sleeve 25 which extends lengthwise around the body member 20 from one small clamping ferrule to the other. The ends 26 and 27 of the sleeve 25 are oblique, to compensate for the webs 12 to 15 and yet extend along the outside surfaces of the ferrules 9 and 10.

Loosely hanging from or lying upon the sleeve 25 are cords 28 which are sewn to the sleeve, as suggested at 29, adjacent the mid-points of the cords, freeing the ends of the cords. There are sufficient cords around the circumference of the sleeve to substantially conceal the sleeve, and the cords flop over and substantially cover the metal clamp 8, top and bottom.

The cords may be sewn to the sleeve 25, when the sleeve is in a flat piece. Then the edges of the flat material may be sewn together in sleeve form, as suggested by the seam 30. The sleeve, together with the loose cord ends, may be chemically treated to pick up dust, and thereby serve as a dust mop when assembled.

The use of the present mop is believed clear, since it is useful for any purpose for which other dust mops are used, and has the added advantages hereinbefore stated.

In assembling, the handle is fastened in the large ferrule 7 by means of the screw 17. One countersunk end 22 of the body member 20 is inserted in the ferrule 10, when the spring clamp 8 is moved to an open position, against the inherent resilience therein. Such resilience causes the ferrule 10 to grip such end, when the clamp 8 is released.

The sleeve 25 is then slid lengthwise on the body member 20, substantially to the position shown in Fig. 1. Thereupon the other end 21 of the body member is clamped within the ferrule 9. The wing nut 19 is screwed tight to maintain

the body member ends in such clamped positions.

For washing, repairing or replacing the sleeve 25, the foregoing operation is reversed to remove same.

While I have illustrated and described what I now regard as the preferred embodiment of my invention, the construction is, of course, subject to modifications without departing from the spirit and scope of my invention. I, therefore, do not wish to restrict myself to the particular form of construction illustrated and described, but desire to avail myself of all modifications that may fall within the scope of the appended claims.

Having thus described my invention, what I claim and desire to secure by Letters Patent is: 15

1. A mop comprising a handle, a bowed, resilient rubber member forming a loop, the member having circumferential countersinks adjacent its ends, clamp means gripping the countersunk ends and fastened to the handle adjacent an end there-

5 of, the bowed member extending through said clamp means and having its resilient ends extending rearwardly from said clamp means and positioned at opposite sides of the handle, a sleeve on the bowed member, the sleeve being endwise removable from the said member when an end of the latter is released from the clamp, and cords on the sleeve providing mopping means.

10 2. A mop comprising a handle, a bowed, resilient rubber member forming a loop, the member having circumferential countersinks adjacent its ends, clamp means gripping the countersunk ends and fastened to the handle adjacent an end thereof, and the bowed member extending through said clamp means and having its resilient ends extending from said clamp means at both sides of the countersunk portions and positioned at opposite sides of the handle, and mopping means on said member.
